DISPLAY DEVICE

Herman Harry Hutt, Brooklyn, N. Y.

Application March 6, 1947, Serial No. 732,907

14 Claims. (Cl. 40—125)

1

This invention relates to display devices for use in displaying advertising literature, as well as articles of merchandise associated with literature in a manner to produce an attractive frame-like display and also to render the articles arranged in the display as substantially pilfer-proof. More particularly, the invention deals with display devices comprising detachably and collapsibly related parts, whereby the entire display can be packed in a relatively small package or where numerous devices may be compactly packed for shipment. The novel features of the invention will be best understood from the following description, when taken together with the accompanying drawing, in which certain embodiments of the invention are disclosed and, in which, the separate parts are designated by suitable reference characters in each of the views and, in which:

Fig. 1 is a perspective view of one type of display which I employ, diagrammatically illustrating the method of its use.

Fig. 2 is an edge view of part of the display, as shown in Fig. 1 in collapsed position.

Fig. 3 is a perspective view, diagrammatically illustrating the characterized sheet in its rolled state, prior to assemblage in the display.

Fig. 4 is a partial section on the line 4—4 of Fig. 1.

Fig. 5 is a side edge view of a modified form of supporting frame, which I employ, detached.

Fig. 6 is a partial section on the line 6—6 of Fig. 5.

Fig. 7 is a sectional view through the central portion of a modified form of display which I employ and indicating the use thereof; and

Fig. 8 is a sectional view showing another form of supporting frame, only part of the construction being shown and omitting the display card or sheet.

The purpose of my invention is to provide a display device which, basically, comprising a supporting frame and a sheet or strip, detachable with respect to the frame and forming, of the combination, a frame-like enclosure, wherein the sheet or strip aids in holding the frame parts in assembled and extended position. Further, it is preferred that the sheet or strip be composed of transparent or translucent materials, lithographed or characterized in any desired manner and so as to display, within the frame and rearwardly of said sheet, articles of merchandise which become part of the complete advertising display. Furthermore, the frame, in combination with the sheet, forms an enclosure

2

guarding the articles, placed on display, from being stolen, particularly when the articles are of a small size.

In Figs. 1—4, inclusive, I have shown one adaptation of my invention, in which the frame, generally identified by the reference character 10, is composed of two similar side members 11 and 12, joined at the lower portion thereof and adjacent the rear portion by a connecting strip 13, glued, wire-stitched or otherwise secured to inner surfaces of the sides 11 and 12, as at 14 and 15, respectively. This construction provides collapsing of the parts 11, 12 and 13 in the manner seen in Fig. 2 of the drawing for compact shipment of one or a number of the devices. In the construction shown in Fig. 1, the frame parts 11 and 12 have upwardly and rearwardly curved walls 16 and 17, terminating in rounded upper ends 18 and 19. Said parts have, adjacent their front edges 20, 21, apertures 22, 23 conforming generally to the contour of the edges 20, 21 and terminating in round apertures 24, 25 in the rounded upper ends 18 and 19, respectively. At 26 is shown a sheet or strip which may be composed of any desired material. It is preferred, however, that plastic sheetings of transparent and/or translucent properties be employed and these strips or sheets will be lithographed or otherwise characterized with the display or advertising matter which is intended to be displayed in the resulting frame, as will be apparent.

The normal tendencies of the strip or sheet 26, when composed of the plastic materials, referred to and, in fact, when composed of any stiff type of metal, paper-board, is to extend itself into a flat condition; thus, in the use of the display, the sheet is put into a roll, as seen at 27, in Fig. 3 of the drawing, and held in this condition by a securing band, as at 28. It will, thus, be seen that, in the assemblage of the frame-like display device, after the parts 11, 12 and 13 are extended into the position shown in Fig. 1, the roll is mounted in the apertures 24 and 25, the band 28 is then removed from the roll 27 and the free edge, as at 29, of the strip or sheet, is moved downwardly through the apertures 22 and 23 until the edge 29 reaches the lower extremity of said apertures. The strip or sheet is made of sufficient length so as to, at all times, leave a partial roll in the apertures 24 and 25, as indicated at 27' in Fig. 1 of the drawing. This roll acts as a bracing means for the top of the resulting frame, sufficient frictional engagement being maintained by the expansion of the roll

into firm engagement with the walls of the apertures 24 and 25.

Considering Fig. 1 of the drawing, it is also noted that the edge 29 includes an inturned portion 29' for reinforcing and strengthening this edge. This is desirable as and when the sheets or strips 26 are composed of thin material. The thicknesses are exaggerated in the present illustration simply for the sake of clarity.

At this time, it will also be understood that any desired contour can be provided in the apertures 22 and 23 so long as the contour is such as to permit passage of the strip or sheet therethrough. In the curvature shown, a frictional engagement is maintained between the sheet and the walls of these apertures to so aid in holding the frame in the assembled relationship. These curvatures, or irregularities, will also add to the characteristics of the display.

In Figs. 5 and 6 of the drawing, I have shown a slight modification, wherein I have substituted, for the coupling, bracing and spacing member 13, a detachable member 30, end portions of which are provided adjacent one side edge with notches, as at 31, note Fig. 6. Here each end wall or frame part, similar to the parts 11 and 12 as, for example, the part 32 will have elongated apertures, as at 33 of sufficient length to receive the full width of the strip 30 and the notch 31 is adapted to engage the wall structure of the frame part 32, as seen at 34 in Fig. 6 of the drawing. The apertures 33 are preferably disposed at an inclination, as seen in Fig. 5 of the drawing. Aside from this change, the structure of the part 32 and its companion part, which is not shown, will be the same as the parts 11 and 12. In other words, an aperture 22', similar to the aperture 22, is provided in the part 32.

In Fig. 7 of the drawing, I have shown a different form of frame comprising similar side parts, one of which is shown at 35, these parts being joined by a strap or band 36, similar to the strap or band 13; the part 35 and its companion part has a curved, front and upper edge portion, as seen at 37 and terminates in a rounded member 38 at the upper rear portion thereof, in which is formed an aperture 39 for the reception of a strip or similar roll 40. The part 35 has an aperture 41, substantially paralleling the edge 37 and also extending rearwardly and upwardly, as seen at 41', at the lower portion of the part 35. The end 41' terminates above and in alignment with the upper edge of the strap or band 36 so that the free, flanged end 42 of the sheet or strip 40' of the roll 40, can engage the strap or band 36 in the manner illustrated in Fig. 7. This type of construction forms a lower kind of display which would be placed in positions where the front and top of the display would be visible to the eye.

In Fig. 7, I have indicated, in dot and dash lines at 43, an article of merchandise or a package placed on display and supported primarily by the strap 36, but which can also rest upon the strip or sheet 40'. In this connection, it will also be apparent that the strap 13 may be used as an article support. On the other hand, articles may be arranged directly upon the counter, table or other surface upon which the display is arranged. With the construction shown in Fig. 7, the strip or sheet 40', in its completely rolled state, is assembled in the aperture or apertures of the frame in the same manner as described in connection with the illustration in Fig. 1.

In Fig. 8 of the drawing, I have shown a further modification, wherein 35' represents a frame,

somewhat of the character shown in Fig. 7 and differing therefrom in having an aperture 44 which terminates at the front of the display, near the lower edge thereof, with this construction, instead of employing the strap, as at 36, in Fig. 7, I employ a base or platform sheet 45 which will extend a distance greater than the distance between the proposed spacing of the frame sides, one of which being shown at 35'. The base, adjacent its ends, has elongated apertures, as at 46, to receive coupling tongues 47, at the lower portion of the frame sides, as for example, the side 35'. Here, the base plate will form the support for the articles which will facilitate removal of the complete unit from a supporting surface without displacing the articles.

The structure of the device, as illustrated in the accompanying drawing, is primarily for what may be termed large types of displays. In small displays and where reinforcement is not essential, the strip or sheet itself may be utilized to join the frame sides by reason of the frictional engagement between the display or advertising sheet and said frame sides, as a result of the inherent properties of the strip or sheet to normally extend itself to a flat condition. In this connection, it will be apparent that the greater the offset or curvature in the apertures in which the strip or sheet is arranged, the greater the stiffness or rigidity to the resulting complete frame assemblage. In other words, it may be said that the strip or sheet tensionally engages the frame parts and this tensional engagement contributes rigidity to the resulting enclosure or frame.

For sake of description, the apertures in the respective frame parts, for example, the apertures 22, 23, 22', 40' and 44, may be said to comprise channels or passages for guiding and supporting side edge portions of the sheet and extending into enlarged openings, at one end thereof.

It will be apparent that, with devices of the kind under consideration, the frame parts may be constructed of substantial material so as to adapt the same to long use or service and, from time to time, new advertising or display sheets or strips can be inserted in the frame in periodically changing the displays.

Having fully described my invention, what I claim as new and desire to secure by Letters Patent is:

1. A display device of the character described comprising a pair of side frame parts, each part having identical apertures of predetermined irregular curved contour, said apertures terminating, at one common end, in large apertures, a flexible display sheet having at one end a roll adapted for insertion in the large apertures of said frames, the remainder of the sheet being arranged in the first-named curved apertures, and said sheet frictionally engaging said apertures in joining said frame parts and spacing said parts one from the other.

2. A display device of the character described comprising a pair of side frame parts, each part having identical apertures of predetermined irregular curved contour, said apertures terminating, at one common end, in large apertures, a flexible display sheet having at one end a roll adapted for insertion in the large apertures of said frames, the remainder of the sheet being arranged in the first-named curved apertures, said sheet frictionally engaging said apertures in joining said frame parts and spacing said parts one from the other.

other, and means independent of said sheet for bracing and spacing said frame parts.

3. A display device of the character described comprising a pair of side frame parts, each part having identical apertures of predetermined irregular curved contour, said apertures terminating, at one common end, in large apertures, a flexible display sheet having at one end a roll adapted for insertion in the large apertures of said frames, the remainder of the sheet being arranged in the first named curved apertures, said sheet frictionally engaging said apertures in joining said frame parts and spacing said parts one from the other, means independent of said sheet for bracing and spacing said frame parts, and said means being foldable with respect to the frame parts.

4. A display device of the character described comprising a pair of side frame parts, each part having identical apertures of predetermined irregular curved contour, said apertures terminating, at one common end, in large apertures, a flexible display sheet having at one end a roll adapted for insertion in the large apertures of said frames, the remainder of the sheet being arranged in the first named curved apertures, said sheet frictionally engaging said apertures in joining said frame parts and spacing said parts one from the other, means independent of said sheet for bracing and spacing said frame parts, and said means being foldable with respect to the frame parts.

5. A display device of the character described comprising a pair of side frame parts, each part having identical apertures of predetermined irregular contour, said apertures terminating, at one end, in large apertures, a display sheet assuming a roll adapted for insertion in the large apertures of said frames, one end portion of the sheet being adapted to extend through and be guided by the first named apertures in joining said frame parts and spacing said parts one from the other, means independent of said sheet for bracing and spacing said frame parts, and the free end portion of said sheet having means engaging said last named means.

6. A display device of the class described comprising a pair of similar side frame parts, a sheet having the properties of extending itself to flat condition, means supporting the sheet in rolled condition, said frame parts having large openings for reception of the rolled sheet, and each frame part having alined channels of common contour extending from said openings, whereby said sheet may be unwound from the roll and guided in the frame parts by said channels to form a wall portion joining said frame parts.

7. A display device of the class described comprising a pair of similar side frame parts, a sheet having the properties of extending itself to flat condition, means supporting the sheet in rolled condition, said frame parts having large openings for reception of the rolled sheet, each frame part having alined channels of common contour extending from said openings, whereby said sheet may be unwound from the roll and guided in the frame parts by said channels to form a wall portion joining said frame parts, and means spaced with respect to the apertures of said frame parts for joining and spacing said frame parts.

8. A display device of the class described comprising a pair of similar side frame parts, a sheet having the properties of extending itself to flat condition, means supporting the sheet in rolled condition, said frame parts having large openings for reception of the rolled sheet, each frame

5 part having alined channels of common contour extending from said openings, whereby said sheet may be unwound from the roll and guided in the frame parts by said channels to form a wall portion joining said frame parts, means spaced with respect to the apertures of said frame parts for joining and spacing said frame parts, said sheet being composed of transparent material, and said last named means forming an article support rearwardly of the sheet and visible through said sheet.

10 9. A display device of the class described comprising a pair of similar side frame parts, a sheet having the properties of extending itself to flat condition, means supporting the sheet in rolled condition, said frame parts having large openings for reception of the rolled sheet, each frame part having alined channels of common contour extending from said openings, whereby said sheet may be unwound from the roll and guided in the frame parts by said channels to form a wall portion joining said frame parts, means spaced with respect to the apertures of said frame parts for joining and spacing said frame parts, said sheet being composed of transparent material, said last named means forming an article support rearwardly of the sheet and visible through said sheet, the free edge terminating in a flange, and said flange engaging said last named means.

30 10. A display device of the character described comprising a pair of frame parts, said frame parts having common elongated channels of irregular contour, a flexible sheet adapted to be arranged in the channels of the frame parts and flexed to conform with the contour of said channels in support and spacing of the frame parts one with respect to the other, means maintaining one end of the sheet in rolled condition within the frame parts for reinforcing the coupling between the frame parts, and the other end portion of the sheet forming a support for articles to be displayed within the device.

35 11. A display device of the character described comprising a pair of frame parts, said frame parts having common elongated channels of irregular contour, a flexible sheet adapted to be arranged in the channels of the frame parts and flexed to conform with the contour of said channels in support and spacing of the frame parts one with respect to the other, means maintaining one end of the sheet in rolled condition within the frame parts for reinforcing the coupling between the frame parts, said channels having substantially horizontal portions in the frame parts, the other 40 end portion of the sheet being arranged in said horizontal portions in forming a support for articles to be displayed within the device, and means on the frame parts engaging the last named end of said sheet to reinforce said end portion of the sheet.

45 12. A display device of the class described comprising a bottom member, upstanding frame parts, at end portions of the bottom member, means comprising a rolled sheet joining and bracing upper portions of the frame parts, said frame parts having common and alined channels of irregular contour, in which side edge portions of the sheet of said roll are adapted to be arranged in further spacing and supporting the frame parts, said sheet being composed of plastic material, and the channels arranging the sheet in the frame parts to form an article supporting portion in the resulting device.

50 13. A display device of the character described comprising a pair of frame parts, said frame parts

having common elongated channels of irregular reversely curved contour, a flexible sheet adapted to be arranged in and frictionally engaging the channels of the frame parts in flexure of the sheet to conform with the contour of said channels, and frictional engagement of the sheet with the channels of said parts serving to couple and space the frame parts one with respect to the other.

14. A display device of the character described comprising a pair of frame parts, said frame parts having common elongated channels of irregular reversely curved contour, a flexible sheet adapted to be arranged in and frictionally engaging the channels of the frame parts in flexure of the sheet to conform with the contour of said channels,

frictional engagement of the sheet with the channels of said parts serving to couple and space the frame parts one with respect to the other, and means maintaining one end of the sheet in rolled condition within the frame parts for reinforcing the coupling between the frame parts.
